United States Patent

Des. 241,921
Patented Oct. 19, 1976

241,921

HAND CALCULATOR

Paul Foster, Monroeville, Pa., assignor to Action
Industries, Inc., Cheswick, Pa.

Filed May 30, 1975, Ser. No. 582,354

Term of patent 14 years

Int. Cl. D10—99

U.S. Cl. D10—97

FIG. 2.

FIG. 1.

FIG. 3.

FIG. 1 is a front elevational view of a hand calculator showing my new design;

FIG. 2 is a top plan view thereof, the bottom being flat, plain and unornamented; and

FIG. 3 is a rear elevational view thereof.

I claim:

The ornamental design for a hand calculator, as shown and described.
